[57] CLAIM

The ornamental design for an automobile tire, as shown
and described.

DESCRIPTION

FIG. 1 is a perspective view of an automobile tire showing
my new design, it being understood that the tread
design is repeated uniformly throughout the circumfer-
ence of the tire and the opposite side is the same as that
shown;

FIG. 2 is a front elevational view thereof; and

FIG. 3 is a side elevational view thereof.
